ATTACHMENT FOR RIBBON MACHINES

Leo A. Schmitt, Washington, D. C.

Application December 9, 1942, Serial No. 468,417

9 Claims. (Cl. 164—89)

This invention relates to new and useful improvements in attachments for machines employing ribbons or the like and has for an object to provide an attachment for producing a duplicate ribbon or web simultaneously with the production of the ribbon or web on the machine to which it is attached.

Another object of the invention is the provision of an attachment of the aforesaid character which is highly suitable for ribbon duplication on a ribbon perforating machine, such as the "Monotype keyboard" machine, of a composing system.

A further object of the invention resides in the provision of a ribbon duplicating machine which is designed for rapid and detachable connection with a ribbon treating machine.

Still another object of the invention is to provide an attachment of the above character which is relatively simple in construction and efficient in operation.

Other objects and advantages of the invention will become apparent as the description progresses.

In the accompanying drawings which illustrate one form of the invention,

Figure 1 is a perspective view of the body and some of the associated parts of the attachment,

Figure 2 is a top plan view of the same with additional parts,

Figure 3 is a vertical sectional view through the attachment mounted on a perforating machine,

Figure 4 is a fragmentary elevational view of one of the supply shaft bearings,

Figure 5 is an enlarged section taken on line 5—5 of Figure 2,

Figure 6 is a transverse section taken on line 6—6 of Figure 5,

Figure 7 is a perspective view of a tightener device,

Figure 8 is a side elevation of a drive pulley connection, and

Figure 9 is an edge view of the same partly in section.

Referring to the drawings, wherein like reference characters denote like parts throughout, the support frame generally indicated at F embodies a pair of complementary side sections 10 and 11, each of which is of approximately arcuate configuration and advantageously of flat plate like rigid material such as metal.

These sections are fixedly united in spaced parallel relation by a medially disposed spacer bar 12 flanged at the ends for connection with the

sections by rivets or other suitable fastening elements 13. A similar bar 14 extends between and connects with the sections adjacent what I term the front end. This constitutes the main frame structure and when employed in conjunction with a perforating machine of the type shown in Figure 3 the plate sections assume vertical positions. At the rear end, each side section has a longitudinal extension 15 bent to form an inward offset with the outer portion provided with a bearing slot 16. A forward extension 17 on each side section terminates in an essentially disk shaped end piece 18 having a center bearing opening 19. At the rear lower part each of these sections is shaped to provide an outwardly offset obliquely depending support leg 20 having an inwardly projecting boss 21 at its lower end. The lower front part at each side of the frame has a depending straight lug 22 immediately rearward of an outwardly offset arcuate claw 23 which may advantageously be in the form of a downwardly and forwardly directed quadrant member.

To the outer side of the frame section 10 is fastened a longitudinally disposed bracket 24 in the form of a bar having a U-shaped portion at the extension 17 and a rear portion secured flat against the frame. A spindle 25 is extended transversely through bearing apertures in the U-shaped bar and the center of the adjacent disk 18. An inwardly projecting portion of this spindle extends through the center opening of a grooved pulley 26 which is fixed thereon while the outer projection is fitted with a nut 27. A sleeve 28 having an oil aperture 29 is mounted between the frame extension and the bracket and incloses the intermediate portion of the spindle. The inner face of the pulley 26 carries an eccentrically disposed stud 30.

On the outer face of the front extension of the frame 11 is secured a laterally offset bracket 31 between which and the frame element 17 is fixed a transversely arranged sleeve 32 having its bore aligned with the opening 19. In this sleeve is loosely fitted a spindle 33 to which are secured a pair of pins 34 projecting through longitudinal slots 35 in the upper and lower portions of the sleeve 32. A compression spring 36 is coiled about the spindle between the pins and the outer closed end of the sleeve so as to yieldingly urge the spindle to an inward position whereat a part of the spindle, with a reduced nose 37, protrudes inwardly of the frame in transverse alignment with spindle 25. A lever 38 is formed at one end with a hooked extension 39 pivotally and slidably

engaging a slotted lip 40 on the forward end of the bracket 31. The opposite end of this lever has a bifurcation 41 whose divided prongs encircle and firmly grip the respective pins 34. Thus, outward pivoted movement of the lever 38 will effect retraction of the spindle 33.

On the outer face of each rearward frame extension 15 is mounted a yoke member 42 having the lower arm 43 extending longitudinally at the lower end of the bearing slot 16. This arm has an elongated slot 44 through which a stop stud 45 connected to the support 15 projects. The complementary arm 46 of the yoke normally assumes a longitudinal position across the top of slot 16 with a substantial portion projecting above the top edge of the extension, as shown in full lines at Figure 4. At the rear end of the yoke is formed a vertically laterally projecting lip 47 to which is fixed the forward end of a guide stem 48 disposed to slide through an aperture 49 in the transverse offset of the frame extension. The lip 47 also provides a projection highly suitable for manually retracting the yoke to release the supply shaft in order to mount a new roll thereon. A coiled compression spring 50 is sleeved about the stem between the offset and the lip to resiliently thrust the yoke to its outward position limited by the stop stud.

To employ the attachment in association with a web feeding machine, as for example with a machine known as the "Monotype keyboard ribbon perforator" it is mounted so that the arcuate claws fit against and partly under the outer front bearing bosses, as illustrated at Figure 3, with the lugs 22 at the inner faces of the perforator frame and the bottom longitudinal edges of the side sections 10 and 11 on corresponding top edges of the machine. When thus positioned the bosses 21 can be slidably fitted into the slotted bearings of the machine outwardly of a shaft journaled therein. In this arrangement the attachment frame is firmly seated although quickly and easily detachable.

A supply roll of ribbon of a width corresponding to that of the machine ribbon is placed on the attachment with a supply shaft, indicated at 51, extended through the center. This shaft has reduced end journals which are placed upon the rear top edges of the extensions 15 and, as the shaft carrying roll is moved inward, strike the outer vertical edges of the upwardly projecting yoke arms 46. Continued inward movement of the roll forces the yokes to retracted positions, as shown in dotted lines at Figure 4, so as to open the slots 16 and allow the roll shaft journals to drop into these slots whereupon the springs restore the yokes to normally outward positions and lock the shaft against displacement. This provides a conveniently operable means for locking the feed roll in position. A ribbon take-up spool is mounted on the front end of the frame and is placed in position by sliding the bore at one end over the non-sliding spindle 25 with an off center aperture in the spool end fitted over the stud 30. The opposite end of the spool is mounted in position by initially depressing the lever plate 38 to retract the spindle 33 whereupon the spool bore is aligned with the retracted spindle which, upon release of the lever 38, is projected by the spring 36 to enter the bore of the spool.

The drive spindle may be effectively driven through the medium of an endless drive element 52, which may advantageously be of the helical wire resilient type trained over the peripheral

groove of pulley 26 and held against displacement by an arcuate guard flange 53 formed on the frame. The perforating machine, such as the Monotype machine hereinbefore indicated, has a ratchet actuated paper wind shaft inserted into a drive disk equipped with an eccentrically arranged pin. To provide for driving connection with this disk a detachable pulley member 54 is fitted thereon. This member is in the form of a circular cap having an internal groove 55 adjacent a web 56 with a resilient split expansion ring 57 in the groove. The periphery of this cap is reversely curved to also provide an external groove 55—a for the accommodation of a drive element such as the spring drive member 52. The corrugation forming the groove 55—a is axially slotted to render the same resilient for sliding the cap over the machine drive disk. It is also to be noted that the cap web 56 has a keyhole slot 58 for fitting over the pin on the disk to effect a positive drive connection. This construction affords means for driving the winding spool on the attachment by and in unison with the winder on the machine.

25 In order to preclude the formation of folds or excessive looseness of the ribbon on and as it unrolls from the supply roll a presser bar 59 secured to the outer ends of a pair of transversely spaced arms 60 frictionally bears on the roll in a position parallel with its axis. The inner ends of the arms 60 are pivotally connected to the spacer bar 12. The ribbon reaches between the paper feed wheels and the supply roll on the machine are maintained in taut condition by a 30 tightener device embodying a U-shaped body 61 of rigid wire having an offset 62 at the closed end. The side legs of this body are bent angularly with their free end portions doubled to respectively embrace the grooved center parts of a 35 pair of round bar weight sections 63. The extremities of the wire are bent inward at the bends to provide pivots 64 resiliently held in bores 65 extending inward at the outer ends of the support legs 20. Thus, sufficient tension is applied 40 to the ribbons to obviate undue looseness without danger of breakage.

This arrangement affords means whereby a 45 duplicate ribbon carried by the attachment is fed under the feed wheels of and subjected to the perforating action of reciprocatory punches of a perforating machine to produce a duplicate ribbon simultaneously with the production of the original ribbon. Such a duplicate can effect considerable saving in time and labor especially in connection with printing involving repetition of subject matter such as box headings in tables and the like. Furthermore, the two ribbons could be employed upon a pair of casting units operated by a single workman.

60 It is to be understood that the form of the invention herein shown and described is to be as a preferred example of the same and that various changes as to shape, size and arrangement of parts may be resorted to without departing from the spirit of the invention and the scope of the subjoined claims.

What I claim as my invention is:

1. In an attachment of the character described, a frame having a pair of spaced apart side sections, each of the said side sections having an attaching claw at the lower front end and a supporting boss at the lower rear end, a pair of complementary shaft supporting bearings at the upper rear end of the frame, and a pair of transversely opposed winding spool supporting spin-

dles mounted at the front upper part of the frame.

2. In an attachment of the character described, a frame having a pair of spaced apart side sections, each of the said side sections having an attaching claw at the lower front end and a supporting boss at the lower rear end, a pair of complementary shaft supporting bearings at the upper rear end of the frame, a pair of transversely opposed winding spool supporting spindles mounted at the front upper part of the frame, one of the said spindles being axially retractible, and a lever hingedly mounted on the frame and connected with the retractible spindle for selectively retracting the same.

3. In an attachment of the character described, a frame having a pair of spaced apart side sections, each of the said side sections having an attaching claw at the lower front end and a supporting boss at the lower rear end, a pair of complementary shaft supporting bearings at the upper rear end of the frame, a pair of transversely opposed winding spool supporting spindles mounted at the front upper part of the frame, one of the said spindles being axially retractible, a lever hingedly mounted on the frame and connected with the retractible spindle for selectively retracting the same, the other of the spindles being rotatably mounted on the frame, and a drive pulley fixed on the same last mentioned spindle.

4. In an attachment of the character described, a frame having a pair of spaced apart side sections, each of the said side sections having an attaching claw at the lower front end and a supporting boss at the lower rear end, a pair of complementary shaft supporting bearings at the upper rear end of the frame, a pair of transversely opposed winding spool supporting spindles mounted at the front upper part of the frame, one of the said spindles being axially retractible, a lever hingedly mounted on the frame and connected with the retractible spindle for selectively retracting the same, the other of the spindles being rotatably mounted on the frame, a drive pulley fixed on the same last mentioned spindle, and means on each shaft supporting bearing for releasably locking a supply roll shaft, the said shaft locking means including spring projected yoke members disposed to releasably embrace the supply roll shaft ends.

5. In combination with a ribbon feeding machine and an attachment mounted thereon for feeding a duplicate ribbon through the machine, of a pulley cap having a resilient periphery closed at one end by a web, the said web having a key-hole slot adapted to fit over the stem and eccentric pin of a winding disk on the machine to effect a driving connection, the said periphery of the cap having an internal annular groove and an external groove, and a split resilient expansion ring fitted in the internal groove of the cap.

6. In combination with a ribbon perforating machine having a frame provided with laterally projecting bearing bosses at one end and slotted bearings at the other end, an attachment com-

prising a frame having side sections adapted to seat upon the sides of the perforating machine frame, a pair of curved elements at one end of the attachment frame disposed to engage the bosses on the machine, a pair of projections adapted to fit into the bearing slots of the machine, means for supporting a ribbon supply roll transversely at one end of the attachment, and means at the opposite end of the attachment for supporting a winding spool transversely thereon, whereby a ribbon on the attachment can be fed through the perforating machine simultaneously with the ribbon on the latter.

7. An attachment for a ribbon machine of the type having longitudinally disposed seat forming surfaces on the top and provided with bearing slots spaced transversely of their axis from bossed bearings, comprising a frame having the bottom adapted for seating on the seat forming surfaces of the machine, projections on the frame disposed to seat in the bearing slots, means on the frame engageable with the bossed bearings to hold the frame against tilting, and bearings at opposite ends of the frame to support shafts of supply and take-up rolls of ribbon to be fed through the machine.

8. An attachment for a ribbon machine of the type having bearings to support the shafts of spaced apart transverse ribbon supply and take-up rolls disposed for feeding a ribbon under a platen roll below and intermediate the said rolls, comprising a frame adapted for seating on the machine, means on the frame engageable with the machine for removably holding the attachment in operative position, bearing means at one end of the frame for rotatably supporting a supply roll parallel with and offset transversely outward with relation to the supply roll of the machine, and bearing means at the opposite end of the frame for rotatably supporting a take-up roll parallel with and transversely inward with relation to the take-up roll of the machine whereby to feed a duplicate ribbon under the platen roll simultaneously and in contiguous relation with the ribbon of the machine.

9. An attachment for a ribbon machine of the type having the top provided with seating surfaces with bearings thereat for rotatably supporting spaced parallel ribbon supply and take-up rolls disposed for feeding a ribbon under a platen roll below the said rolls, comprising a frame adapted for seating on the seating surfaces, means on the frame engageable with the machine bearings for detachably holding the frame in operative position on the machine, bearing means at one end of the frame for rotatably supporting a supply ribbon roll parallel with and offset transversely outward with relation to the supply roll of the machine, and bearing means at the opposite end of the frame for rotatably supporting a take-up roll parallel with and transversely inward with relation to the take-up roll of the machine whereby to feed a ribbon under the platen roll simultaneously with the ribbon on the machine.
